UNITED STATES PATENT OFFICE

WILLIAM H. ROBBINS, OF SPRINGFIELD, OHIO, ASSIGNOR TO THE WILLIAMS COMPANY,
OF LONDON, OHIO, A CORPORATION OF OHIO

STEEL WOOL PAD

Application filed February 7, 1927. Serial No. 166,475.

My invention relates to a pad and particularly to steel wool pads.

It is the object of my invention to provide a combined steel wool and textile pad in which the textile material lends strength and absorbing power to the pad. In particular it is my object to form a pad in which the strands of wool and textile material such as yarn are straight.

10 Referring to the drawings,

Fig. 1 is a bottom plan view of the pad with one layer of steel wool and alternate strands of the adjacent layer of yarn removed.

15 Fig. 2 is a section of the complete pad on the line 2—2 of Fig. 1, looking in the direction of the arrows.

Referring to the drawings in detail, it will be observed that the pad is formed of alternate layers of steel wool designated 1 between which are located threads of yarn 2, both the wool and yarn being arranged in parallel lines transversely of the vertical height of the pad. The ends of the yarn and 25 of the wool are cut off in suitable configuration to form a pad which preferably has a cup shaped recess formed by the sidewalls 3 of the pad. In this recess can be located a cake of soap 4.

30 The textile threads lend strength to the structure and also are adapted to absorb moisture and maintain the soap in a moist condition to facilitate the abrading or scrubbing operation.

35 It will be understood that I desire to comprehend within my invention such modifications as may be comprehended within the scope of the following claims.

Having thus fully described my invention, 40 what I claim is new and desire to secure by Letters Patent, is:—

1. In combination a pad having a working face formed of a plurality of alternate laminations of parallel strands of textile material interspersed with layers of steel wool.

2. In a pad a plurality of straight steel wool strands and straight textile strands arranged in alternate layers.

3. In a pad a plurality of steel wool and 50 textile strands arranged alternately in

straight lines in cup shaped form and a detachable body of soap mounted in said cup whereby the steel wool will cleanse an object treated by the pad, the soap will clean the object, and the textile material will support 55 the wool and retain the moisture in the pad for cooperation with the soap.

4. In a pad the combination of steel wool and textile material, the ends of said textile material being exposed on the margin of the 60 pad whereby moisture will be conveyed through the pad and retained therein by said textile material.

5. In a pad the combination of steel wool and textile material, the ends of said textile 65 material being exposed on the margin of the pad whereby moisture will be conveyed through the pad and retained therein by said textile material, a cup formed in said pad, the inner walls of which are engaged by the 70 free ends of said textile material, and a cake of soap mounted in said cup so that the moisture is conveyed through the pad to the soap.

In testimony whereof, I affix my signature.
